UNITED STATES PATENT OFFICE.

CHRISTOPHER L. STANGE, OF ST. LOUIS, MISSOURI, ASSIGNOR TO THE GRAND COUNCIL OF THE ORDER OF DE MOLAY, OF ST. LOUIS, MISSOURI.

DESIGN FOR A RING.

Application filed May 22, 1926. Serial No. 17,812. Term of patent 3½ years.

To all whom it may concern:

Be it known that I, CHRISTOPHER L. STANGE, a citizen of the United States, and a resident of the city of St. Louis, State of Missouri, have invented a new, original and ornamental Design for Ring, of which the following is a specification, reference being had to the accompanying drawing, forming part thereof.

Said drawing is a front perspective view of a ring embodying my invention.

I claim

The ornamental design for a ring, as shown.

CHRISTOPHER L. STANGE.
